SHOE

Calvin C. Klaus, Highland, Ill.

Application February 23, 1939, Serial No. 257,831

2 Claims. (Cl. 36—8.5)

My invention has relation to improvements in shoes and consists of the novel features of construction more fully set forth in the specification and pointed out in the claims.

5 The invention is primarily directed to a shoe construction comprising a combination inner sole and counter rigidly constructed so as to hold its natural shape and embody strength.

The primary object of the invention is the 10 formation of the insole and counter of a single piece of leather so shaped that one side of the counter is turned upwardly from the insole and of course formed integrally therewith, and the other side of the counter overlapping the insole and bedasted thereto.

15 The construction of the shoe whereby this object is accomplished will be better understood from a detailed description thereof in connection with the accompanying drawing, in which:

Fig. 1 is a side elevation of the combination 20 insole and counter; Fig. 2 is a top plan thereof; Fig. 3 is a development showing the blank from which the inner sole and counter are formed; and Fig. 4 is a vertical cross-section taken on the line 4—4 of Fig. 1.

25 Referring to the drawing my improved shoe embodies an inner sole 8 and a counter 9 formed of a single piece of leather blanked out as shown in Figure 3. Figures 1 and 2 show the counter erected and the side 10 thereof, which constitutes flap 11 in the blank 12, securely fastened to the inner sole.

A tongue 13 is formed in the blank 12 for reinforcing the forepart of the counter and receiving 30 the flap 11, and the counter 9 is bent upwardly and said flap brought around the heel part of

the blank 12 to form the heel of the counter. That part of the flap 11 immediately adjacent to the heel part of the blank 12 is scalloped as shown at 15 so that as the flap is bent substantially along the dotted line X, the marginal portion 16 thereof, including the scallops 15, may be turned beneath the heel part of the blank and cemented and pegged or slugged thereto as shown in Figure 2. The tongue 13 is cemented on the inside of the flap 11 after the latter has been brought around to form one side of the counter 9.

When the combination insole and counter has thus been built up the upper and the outer sole are secured to the forepart of the inner sole by Goodyear welt and sole stitching (or some other well-known manner), and the shank and outer sole are secured together by double slugging or wood pegging as desired. Of course if the shoe is to be a welt shoe the marginal channel 17 is provided in the usual manner.

Having described my invention, I claim:

1. A blank for making combination insoles and counters comprising a part of the general shape of a shoe insole and a flap projecting rearwardly from one side of said insole part and shaped to form the counter, and a second flap on the insole part of the blank opposite to the first flap.

2. In a shoe, the combination of an insole and counter formed integrally therewith along the inner margin of the insole, a flap extending around the rear and outer margin of the counter, a second flap projecting from the rear part of the insole, and means for securing the first flap to the insole and means for securing the second flap to the counter.

CALVIN C. KLAUS.
